UNITED STATES PATENT OFFICE.

LEON J. SCHLOSS, OF SPOKANE, WASHINGTON.

JEWELRY GUARD.

Application filed April 22, 1921. Serial No. 463,504.

To all whom it may concern:

Be it known that I, LEON J. SCHLOSS, a citizen of the United States, residing at Spokane, in the county of Spokane and State of Washington, have invented certain new and useful Improvements in Jewelry Guards, of which the following is a specification.

This invention relates to guards for jewelry, and the primary object of the invention is to provide an improved device for preventing the accidental displacement of all kinds of jewelry, such as cuff links, brooches, fraternity pins or the like, from the parts of the clothing with which they are associated, and the consequent loss thereof. Possibly of all jewelry, more cuff links are lost than any other kind, and more trouble has arisen in keeping the same in correct position. The continual loss thereof has given way to using of cheap cuff links and while jewelers and others have made considerable experiments in an effort to provide a suitable guard for cuff links, no satisfactory guard has yet been placed upon the market. The guards which have been so far designed, are more or less clumsy and can be easily seen, thus detracting from the appearance of the cuff links.

It is therefore a further object of the invention to provide a guard which is particularly adaptable for cuff links and which embodies a member arranged to protrude through the cuff having an adjustable head adapted to frictionally engage the cuff and to absolutely preclude displacement of the link from the cuff or movement thereof on the cuff.

A still further object of the invention is to provide an improved loss preventing guard which can be either placed upon the jewelry at the time of manufacture thereof or can be sold as an independent article of manufacture and secured to cuff links and other jewelry already manufactured and on the market or in use.

A still further object of the invention is to provide an improved jewelry guard of the above character, which will be durable and efficient in use, one that will be simple and easy to manufacture, and one which can be placed upon the market at a reasonable cost.

With these and other objects in view, the invention consists in the novel construction, arrangement and formation of parts as will be hereinafter more specifically described,

claimed and illustrated in the accompanying drawings, forming a part of this specification, in which drawings:

Figure 1 is a side elevation of a soft cuff with one flap thereof turned back, showing a cuff link in position thereon provided with the improved guard.

Figure 2 is an enlarged side elevation of a cuff link or button, showing the improved guard incorporated therewith, the adjustable head or nut of the guard being shown in section.

Figure 3 is an end elevation of a starched cuff showing a cuff link or button connected thereto provided with a modified form of the guard.

Figure 4 is an enlarged fragmentary side elevation of the cuff button provided with a modified form of guard, and

Figure 5 is a detail perspective view of a guard which is adapted to be secured to cuff links or other article of jewelry after the same has been manufactured and placed upon the market.

Referring to the drawings in detail, wherein similar reference characters designate corresponding parts throughout the several views, the letter A indicates the improved guard and B a cuff link or button associated with a cuff C, which is of the unstarched or French roll variety.

While the improved guard has been shown in connection with a cuff button, for which it has been primarily designed, it is to be understood that the same is to be used with any type of jewelry which is susceptible of being lost, such as breast pins, brooches, fraternity pins, stick pins and the like.

The button or cuff link B which has merely been shown for the purpose of illustrating one use of the invention is of the ordinary or any preferred construction, and as shown includes the connecting shank 10, the relatively large head 11, which is usually ornamented, and the relatively small head 12. The connecting shank 10 for the heads 11 and 12 is of course arranged substantially at the central portion of the head and is adapted to extend through the button holes 13 in the inner and outer flaps 14 and 15 of the cuff C which is also of the usual or any preferred construction.

The improved guard A includes a stud or post 16, the inner end of which is adapted to be secured in any preferred manner to the inner surface of the enlarged head 11. The

stud or post 16 is preferably arranged in spaced relation to the shank 10, and while the same has been shown carried by the head 11, it is also to be understood that the same can be, if so desired, secured to the inner surface of the relatively small head 12. The stud or post 16 is provided with external screw threads and the free end thereof is sharpened as at 17. The sharpened end of the stud or post permits the same to be readily pushed through the shirt sleeve or cuff with which it is associated, and prevents the cutting of the material from which the cuff is made as the stud or post is of cylindrical shape and the pointed end thereof merely parts or spreads the threads.

A nut or head 18 is provided for the threaded stud or post 16 and this nut is of a novel form, so as to be particularly adaptable for the purpose intended. The head or nut 18 is provided with an inwardly extending axial bore 19 for receiving the stud or post 16, and can be, if so desired, provided with an annular flange 20 which can have its outer surface serrated or milled so as to permit the ready rotation of the head or nut. The head or nut 18 directly inward of the flange 20 has its outer surface provided with an annular concaved groove 22, which defines a relatively small base 23, and it can be seen that when the device is in use, the relatively small base 23 will engage the fabric of the cuff and tend to bite into the same without tearing the threads thereof and the base will also tend to force the material out around the annular groove 22. The outer surface of the head 18 is preferably formed rounded, as at 24, so as to provide a non-abrading smooth surface for engaging the opposite inner surface of the outer flap 14 of the cuff, so as to prevent the tearing thereof, and this smooth surface of the head also protects the user's arm or hand from the pointed end 17 of the stud or post 16. This form of cuff guard is particularly adaptable for the soft cuff but is not limited to such use.

In use of the improved guard, the cuff button is first inserted through the button holes 13 at one end of the cuff and the stud or post 16 is then inserted through one flap, say the outer flap 15 of the cuff C, after which the nut or head 18 is threaded into tight engagement with the material from which the cuff is formed. This absolutely holds the cuff link against turning movement on the cuff and prevents the accidental loss thereof and the guard is entirely hidden from view.

In Figures 3 and 4 is shown a guard D connected with a button E for attachment with a stiff or starched cuff F, and while this form of guard is particularly adaptable for stiff or starched cuffs, it is to be understood that the guard is applicable for use with un-starched cuffs.

The cuff button or link is also of the usual

or any preferred construction and includes the relatively large head 25 and the relatively small head 26 and the connecting shank 27. The head 26 is adapted to be placed through the button holes 28 of the cuff F in the usual manner. The cuff F is also of the ordinary or any preferred construction or make.

The modified form of attachment designated by the numeral D also includes a threaded post or stud 29, which is secured in any preferred manner in spaced relation to the shank 27 to the inner surface of the relatively large head 25 and this threaded shank is adapted to be forced through the plies of the cuff F. The outer end of the stud or post 29 is also pointed as at 30 so as to facilitate the pushing of the stud through the plies of the cuff and the pointed end is also adapted to spread the threads of the plies instead of cutting the same through.

The head or nut for the stud 29 includes a tubular body 31, the lower end of which is provided with a flared base 32, which might be described as a concavo-convex disc. The inner surface of the tubular body 31 is provided with an internally threaded bore 33 for the reception of the pointed stud, and in order to act as a guard for the stud, a ring or eye 34 is provided. This ring or eye 34 extends in the same plane as the tubular body 31 and has its terminals secured thereto and the body portion of the eye or ring extends diametrically across the outer end of the body in spaced relation thereto. This ring or eye 34 also forms a handle for facilitating the rotation of the head or nut. If so desired the outer edge of the flared base 32 may be serrated or milled so as to permit a ready grip to be obtained thereon so as to facilitate turning of the nut or head. It also can be seen that owing to the fact that the flange or disc is outwardly curved transversely, the flange will have a tendency to be spread when forced into frictional contact with the starched cuff when the head is threaded on the stud, so as to form an intimate contact with the cuff and thereby prevent accidental rotation of the head on the stud.

In use of this form of the invention, the guard is used in exactly the same manner as the guard shown in Figures 1 and 2 and the head 26 is inserted through one of the holes 28 of the cuff F and the threaded stud 29 is forced through the fabric after which the head or nut is threaded thereon into tight engagement with the cuff.

The head is then inserted through the other button hole.

In taking off the shirt at night, the cuff buttons may not be removed from the cuff unless desired, as the loss thereof is absolutely precluded by the guard.

In Figure 5 of the drawings is shown a

novel form of the guard which is adapted to be placed upon all types of jewelry which are already on the market or in actual use, and as shown, this guard which is designated by the letter G includes a flat disc shaped base plate 35, having secured at the axis thereof in any preferred manner the outwardly extending threaded stud 36, which has the outer end pointed as at 37. This stud 36 is adapted to receive a head or nut 38 which can be constructed similar to the head shown in Figures 1 and 2 of the drawings, or similar to the head or nut shown in Figure 3 of the drawings.

15 The base plate 35 is adapted to be secured to the article of jewelry with which the guard is to be associated by solder or the like and the guard is then used in the same manner as the guards shown in Figures 1 to 4 inclusive as heretofore described.

20 From the foregoing description, it can be seen that an exceptionally simple and durable guard has been provided for all kinds of jewelry, which will effectively hold 25 the same in position against accidental displacement or loss.

Changes in details may be made without departing from the spirit or scope of this invention; but,

30 I claim:

1. In a device for preventing loss of jewelry, the combination with a body having an attaching shank, of a guard therefor including a stud secured to the body in spaced relation to the attaching shank and a locking member carried by the stud arranged to be moved into tight engagement with the material with which the body and shank is associated.

40 2. In a device for preventing loss of jewelry, the combination with a body, an attaching shank carried by the body, of a guard for the body including a threaded stud carried by the inner surface of the body and arranged to extend through the fabric with which the article of jewelry is worn, and a head threaded upon said stud arranged to move into engagement with said fabric.

45 3. In a device for preventing loss of jewelry, the combination with a body, and an

attaching shank, of a guard for the body including an inwardly extending pointed threaded stud carried by the body and arranged in spaced relation with the attaching shank, the stud being adapted to be forced through the threads of the fabric with which the article of jewelry is associated, and a nut threaded upon said stud and arranged to be forced into engagement with the fabric through which the stud protrudes, and means carried by said nut arranged to protect the pointed end of the stud.

4. In a device for preventing loss of jewelry, the combination with a body having an attaching shank, of a guard for the body including an externally threaded stud having its inner end secured to the body in spaced parallel relation with the attaching shank, the free end of said stud being pointed for facilitating the forcing of the stud through the fabric with which the piece of jewelry is associated, a locking member for the guard including a body provided with an internally threaded bore arranged to receive the stud, a peripheral flange formed on the body, and a smooth protecting member carried by the body arranged to overlie the pointed end of the stud.

5. The combination with a cuff link including a pair of spaced heads and a shank connecting said heads, of a guard for preventing the loss of said link including an externally threaded stud secured to one of said heads in spaced relation to said shank, and a nut threaded upon said shank.

6. The combination with an article of jewelry, including a body and an attaching shank, of a loss preventing device therefor including a threaded stud secured to the body in spaced parallel relation to the shank, one end of the stud being pointed, a head for association with the stud including a tubular internally threaded body, an outwardly extending annular flange formed on the body curved transversely in cross section, and a ring secured to the tubular body and extending diametrically across the outer end thereof.

LEON J. SCHLOSS.
